UNITED STATES PATENT OFFICE.

ALBERT S. BERTANZETTI AND SILVIO DE PRANPERO, OF FREDERICKTOWN, PENNSYLVANIA; SAID DE PRANPERO ASSIGNOR TO SAID BERTANZETTI.

PRESSURE-OPERATED SWITCH.

Application filed December 4, 1922. Serial No. 604,967.

To all whom it may concern:

Be it known that we, ALBERT S. BERTANZETTI and SILVIO DE PRANPERO, residing at Fredericktown, in the county of Washington and State of Pennsylvania, citizens of the United States, have invented or discovered certain new and useful Improvements in Pressure-Operated Switches, of which improvements the following is a specification.

10 Our invention relates to pressure-operated switches. It finds immediate use in the lubricating system for the engine of an automobile, and in that use we shall show and describe it; but manifestly it is useful, 15 wherever lubricating oil is circulated under forced feed, whether in an automobile or elsewhere. It there constitutes an essential element of a precautionary or safety appliance, to save the car or other machine from 20 injury under conditions which arise in service.

In the accompanying drawings, Fig. I is a diagrammatic view of a circulating system for lubricating oil applied to the crank case 25 of an automobile, to which system our invention is here shown to be applied; Fig. II is a view in vertical section and to larger scale of the pressure-operated switch in which our invention centers.

30 Referring to Fig. I, the crank case of an automobile is indicated in fragmentary manner at 1. From the bottom of the crank case 1 an oil pipe 2 leads, and returns in circuit and opens again within the crank case, but 35 at such particular place as to effect the desired lubrication of the contained bearings. In the line of circulation pipe 2 is arranged a pump 3, and the usual indicator 4 may communicate with pipe 2. All these features 40 are in common and general use, and no more minute description of them is required.

At a suitable point in a horizontal reach of circulation pipe 2 and on the delivery side of pump 3 is introduced the attachment 5 in 45 which our invention centers.

This attachment consists essentially of a cylindrical chamber, to which in Fig. II the reference numeral 5 is particularly applied, rising vertically from a horizontal reach of 50 circulation pipe 2, and with the circulation pipe the cylindrical chamber is in communication. Communication is, however, controlled by a downwardly closing check valve, conveniently formed as a spherical valve 10.

Within the cylinder a piston 6 is reciprocal. 55

Through the cylinder walls at a common level, and in such position as to constitute a stop, defining the lower limit of piston traverse, as presently will appear, extend electrical contact pieces 7, carried in plugs 8 of insulating material. These contact pieces at their inner ends are preferably made conical in shape, and the piston 6 is preferably made correspondingly conical. Furthermore, to 60 the piston is preferably attached a centrally supported plate 9, capable of slight tipping, and upon this plate particularly the conical configuration may be imposed. The piston 6 with its end plate 9 are formed of conducting material, brass or other metal; the cylinder is likewise formed ordinarily of brass, and electrical contact is always maintained between cylinder and piston, and, when the piston descends to the permissible 65 limit, between piston and contact pieces. But the contact pieces always are insulated from the conducting material of the cylinder wall which sustains them. The tipping plate 9 upon piston 6 is provided, to insure electrical 70 contact with both contact pieces on descent of the piston to the permissible limit. 75

We have said that electrical contact is always complete between piston and cylinder. This is ensured by reducing the cylinder 85 bore above and causing the piston stem to be closely engaged thereby. The contact is permeable by air, as the piston rises and falls.

The cylinder 5 is open above, and its bore is enlarged slightly at the upper end, as indicated at 11. We find that by resort to this slight enlargement in the bore of the piston, leakage of oil is effectively prevented. 90

To one contact piece 7 is connected a lamp 95 circuit 12, or a circuit containing a tell-tale device of some other form; to the other is connected a circuit 13 which, being energized, makes ineffective the sparking device or other electrical control of the engine. 100

Operation will readily be understood. So long as oil is circulating under pressure through circulation pipes 2, piston 6 will be held elevated, circuits 12 and 13 will be uncompleted and ineffective. If oil fails, the 105 pump continuing in operation, air accumulating in cylinder 5 will escape, failing to hold the piston elevated. The piston will

descend, the two electrical contacts will be closed, both circuits 12 and 13 will be grounded through cylinder 5, the light or equivalent tell-tale will function, and, the 5 spark failing, the engine will stop. Again, if water accumulates in the crank case it will be circulated, and, collecting, in the cylinder 5, will short circuit the terminals of the two circuits 12 and 13, establishing 10 electrical contact between the terminals 7, and the practical effect will be the same as before. Indeed, it may be remarked that with both circuits each grounds the other when the piston engages both contact pieces, 15 or when water accumulates between the contact pieces.

Thus, whether oil fails or water accumulates, the driver of the car will have advice and his engine will stop.

20 In the practice of the invention the structure may include either or both the circuits 12 and 13, as may be desired.

It remains only to note that when under 25 normal operating conditions the engine is stopped, and with it the pump 3, the valve 10 is effective to retain within cylinder 5

the body of oil there normally accumulated. So while the automobile remains standing the circuits 12 and 13 remain ungrounded (and it is circuit 13 which is of particular 30 importance here). The spark apparatus will continue in active condition when the engine is to be started again.

Manifestly the invention is applicable generally to engine installations, but we 35 have described it in application to an automobile engine specifically, for in that application we have developed it.

We claim as our invention:

In an oil circulating system for a gas 40 engine, a circulation pipe, a pressure chamber in communication with said circulation pipe, a contact piece adapted to be held inactive under accumulated pressure within the chamber against an opposing force, and 45 a check valve controlling the communication between circulation pipe and pressure chamber.

In testimony whereof we have hereunto set our hands.

ALBERT S. BERTANZETTI.
SILVIO DE PRANPERO.
